BOTTLE CARRIER

Barney Rothstein, Wilkes-Barre, Pa., assignor to
Old Fashion Ma's Root Beer Bottling Company,
Wilkes-Barre, Pa.

Application April 7, 1943, Serial No. 482,152

4 Claims. (Cl. 229—52)

The invention relates generally to hand carriers and primarily seeks to provide a novel form of bottle carrier which is strong and durable and can be inexpensively manufactured from heavy paper or cardboard.

It is well known that much difficulty is encountered in the carrying of bottles to and from the market, and much effort has been expended in developing various forms of bottle carriers including hand holds and which are adaptable for conveniently carrying bottles to and from places at which bottled products are purchased. These efforts usually have been directed toward the provision of carriers suitable for carrying the relatively small bottles used in the packaging of carbonated or other beverages. The present invention, while adapted to broader uses, is designed to fill the need for an efficient carrier adaptable to the carrying of larger bottles, such as quart sizes of milk or carbonated water or the like.

An object of the invention is to provide a simple form of bottle carrier of the character stated wherein is provided a central hand hold and bottle dividing wall and a single bottle receptacle of holding compartment at each side of the central wall.

Another object of the invention is to provide a bottle carrier of the character stated that can be collapsed flat without disconnecting any parts thereof, for convenience in storing, shipping or other handling.

Another object of the invention is to provide a bottle carrier of the character stated which is made up from an elongated blank having a central portion large enough to form a base whereon two large bottles may rest uprightly, and two oppositely directed end portions each including an end wall forming portion forming an end extension of the central portion, side flaps adapted to be folded to lie opposite one another and form the side walls of the carrier at one end, and end wall flaps adapted to be folded upon each other to form double walled inner end walls, said double walled inner end walls being adapted to be brought into back to back contacting relation in the finished carrier and stapled or otherwise secured together to form a bottle dividing central wall and hand hold portion.

Another object of the invention is to provide a bottle carrier of the character stated formed from a blank to comprise two like end portions which are brought together to form a bottle dividing wall and hand hold portion and having registering finger receiving apertures therethrough whereby the act of carrying the carrier with fin-

gers through said apertures serves to hold together the component parts or flap portions of the carrier.

With the above and other objects in view that will hereinafter appear, the nature of the invention will be more fully understood by following the detailed description, the appended claims and the several views illustrated in the accompanying drawings.

10 In the drawings:

Figure 1 is a perspective view of a bottle carrier embodying the invention.

Figure 2 is a plan view of the blank from which the carrier is formed.

15 Figure 3 is a vertical cross section taken on the line 3—3 on Figure 4.

Figure 4 is a vertical longitudinal section taken on the line 4—4 on Figure 3.

20 Figure 5 is a horizontal section taken on the line 5—5 on Figure 4.

Figure 6 is a plan view of the carrier collapsed into the flat for storing or shipping purposes.

Figure 7 is a detail sectional perspective view showing one side at one end of the blank folded up.

25 The blank from which the improved carrier structure is formed includes two identical end sections or half portions A joined at a central fold line B. Each half section disposed at each side of the central fold line B includes a rectangular base area 5 defined by the side edges 6, the central fold line B and the end fold line 7 and large enough to receive the base of a single bottle, the two base areas 5, 5 together comprising a base section on which two bottles can be supported, side by side.

30 35 Beyond the end fold line 7 each end section includes an end wall area 8 defined by the respective fold line 7, parallel side fold lines 9, and by the respective V-shaped end terminus 10.

A side wing area 11 extends laterally beyond each fold line 9, and each lateral extension is cross slit as at 12 to limit the shape of the side wall portion to be effective as a bottle embracing side wall and to partially define a hand hold or central divider wall area 13. Both lateral wing

40 45 portions 11 and 13 which extend in longitudinal alignment in the manner illustrated in Figures 2 and 7 are reinforced and connected by a full length reinforcing flap extension 14 which is connected with the wing extensions 11 and 13 at a fold line 15. The wing extensions 13 are

50 55 equipped with registering, finger receiving apertures 16, and each reinforcing flap extension 14 includes a registering recess 17 in the lateral edge extremity thereof.

55 In shaping up the carrier the end walls 8 are

folded uprightly at the fold lines 7, and then the side wing portions 11 are folded into parallel relation about the hinge or fold lines 8. By now folding the respective ends of the end portions of the blank at the fold lines 15 the reinforcing flaps can be brought together in contacting relation as illustrated in Figures 4 and 5 and the wing extensions 13 can be brought into face to face contact in the manner clearly illustrated in Figures 1, 3, 4 and 5 to bring the finger receiving apertures 16 and recesses 17 into registry and to form the central hand hold or bottle separating wall in the manner clearly illustrated in said Figures 1, 3, 4 and 5. The end section portions thus brought together to form the hand hold and dividing wall may be secured in face to face contact by staples 18 or other securing means in the manner clearly illustrated.

With the carrier made up in the manner clearly illustrated in Figures 1 and 4 the compartments provided at opposite sides of the hand hold or dividing wall are adapted to receive two large size bottles with the dividing wall separating the bottles against damaging contact.

It will be obvious that by folding the base areas 5 in face to face contact, either upwardly between the end walls 8, or downwardly as illustrated in Figure 6, and by swinging the side walls 11 laterally about the hinge connections 15 with the hand hold or divider wall, each end wall 8 can be brought into face to face contact with the side wall 11 at the particular side in a manner for completely collapsing the carrier into the flat as illustrated in Figure 6. In the flattened condition illustrated in Figure 6 the carriers can be conveniently stored or shipped.

It is of course to be understood that the details of structure and the arrangement of parts may be variously changed and modified without departing from the spirit and scope of the invention.

I claim:

1. A bottle carrier formed from a paper blank to comprise a base large enough to receive two bottles thereon, a centrally disposed hand hold comprising a wall of a width approximating the width of a bottle to be carried and disposed centrally above and separate from the base and forming a dividing wall between two bottles when the latter are supported on the base, an end wall of a width approximating the width of a bottle and upstanding from each end of said base, and a side wall of a width approximating the width of a bottle and uprightly disposed at each side of each end wall and hingedly connected at one upright edge with the adjacent end wall and at its other upright edge with the adjacent hand hold, said base having a fold line thereacross and equally dividing the same into half portions whereby said half portions can be folded one against the other and said side walls can be swung laterally about their hinge connections with the

hand hold to bring the end walls into face to face parallel relation and collapse the carrier flatwise for storage or shipment.

5 2. A bottle carrier formed from a paper blank comprising a base section 5, 5 of an area for receiving thereon two bottles, and an end extension 8, 11, 13, 14 at each end of said base section, each said end extension being foldable uprightly relative to the base section to form an end wall 8 and including lateral side wall extensions 11, 11 foldable into parallel spaced relation to form bottle embracing side walls 11, 11 and two wall portions 13, 13 foldable in face to face contact to form a hand hold portion, said two hand hold forming wall portions 13, 13 when secured together in face to face contact forming a hand hold and a division wall for separating bottles supported on said base portion.

20 3. A bottle carrier formed from a paper blank comprising a base section 5, 5 of an area for receiving thereon two bottles, and an end extension 8, 11, 13, 14 at each end of said base section, each said end extension being foldable uprightly relative to the base section to form an end wall 8 and including lateral side wall extensions 11, 11 foldable into parallel spaced relation to form bottle embracing side walls 11, 11 and two wall portions 13, 13 foldable in face to face contact to form a hand hold portion, said two wall portions 13, 13 forming endwise extensions of said two side wall extensions 11, 11 in the blank and being separated therefrom by cross slitting 12, 12, and there being included a reinforcing flap 14 extending along and connecting each of said two wall portions 13, 13 and the associated one of the two other side wall extensions 11, 11, and said two hand hold portions when secured together in face to face contact forming a hand hold and a division wall for separating bottles supported on said 25 base portion with the reinforcing flaps 14 folded into and forming a part of said division wall.

4. A bottle carrier formed from a paper blank to comprise a base large enough to receive two bottles thereon, a centrally disposed hand hold 45 comprising a wall of a width approximating the width of a bottle to be carried and disposed centrally above and separate from the base and forming a dividing wall between two bottles when the latter are supported on the base, and wall 50 structures for surrounding a single bottle at each side of said hand hold and including two parallel side walls and an end wall paralleling said centrally disposed wall and connected to said base, said base being foldable upon itself, and the wall 55 structures at each side of the hand hold being collapsible by a lateral swinging of the side walls flatwise one at one side upon another at the opposite side with the end walls in parallel relation to transform the actively set up carrier to flat collapsed form for storage or shipment.

BARNEY ROTHSTEIN.
